UNITED STATES PATENT OFFICE

FREDERICK W. GEISSENHAINER, OF FREEHOLD, NEW JERSEY, AND MATTHEW S. CUMNER,
OF NEW YORK, N. Y.

PRINTING-PRESS.

No. 921,536.

Specification of Letters Patent.

Patented May 11, 1909.

Application filed October 19, 1908. Serial No. 452,332.

To all whom it may concern:

Be it known that we, FREDERICK W. GEISSENHAINER and MATTHEW S. CUMNER, citizens of the United States of America, and residing, respectively, at Freehold, in the county of Monmouth and State of New Jersey, and New York, in the county of New York and State of New York, have invented certain new and useful Improvements in Printing-Presses, of which the following is a specification, such as will enable those skilled in the art to which it appertains to make and use the same.

This invention relates to printing presses and the object thereof is to provide a manually operable press for use in stores, offices, and the like, for the printing of slips, price tags, tickets, etc., required frequently and in quantity, either with permanent, variable, or both permanent and variable subject matter; another object being to provide such a press which prints from a roll of paper; another object being to provide means for detaching the printed objects from the said roll of paper; and another object being to provide means for feeding the said paper to the printing mechanism, and also to provide means whereby but one of either the feeding mechanism or the detaching mechanism is operable at one time.

Our invention is fully described in the following specification, of which the accompanying drawings form a part, in which the separate parts are designated by the same reference characters in all of the views, and in which:—

Figure 1 is a right hand elevation of our printing press, ready for use; Fig. 2 is a left hand elevation thereof; Fig. 3 is a plan view thereof; Fig. 4 is a longitudinal sectional view taken on the line 4—4 of Fig. 3; Fig. 5 is a fragmentary view, similar to Fig. 4, but showing the parts in a different position; Fig. 6 is a view similar to Fig. 5 but with the parts in still a different position; Fig. 7 is an enlarged detail of the construction; Fig. 8 is an enlarged view of the printing roller; Fig. 9 is a section on the line 9—9 of Fig. 8; Fig. 10 is an enlarged view of another detail; Fig. 11 is a partial section on the line 11—11 of Fig. 1; and Fig. 12 is a view of certain gears which we employ.

In the drawings forming a part of this application, we have shown a frame or support 55 a which carries a roller a² at one end thereof,

which is frictionally held against too free movement by means of a brake a³, and which carries a roll of paper a⁴ upon which the printing is to be performed, said paper being carried forwardly between guides a⁵ and a⁶ to the printing mechanism. At the opposite end of the frame a, near the top thereof, is a power shaft b, provided with a hand wheel b² by means of which it is rotated, and said shaft carries a mutilated gear b³ at the right hand end and a similar gear b⁴ at the left hand end thereof.

Directly beneath the shaft b, at the right hand side of the frame, is a stud c upon which are mounted a Geneva gear c², operated by the mutilated gear b³, and an ordinary gear c³ which is connected with and rotated by the Geneva gear c², the gear c³ being enmeshed with a gear c⁴ to the rear thereof and which is secured to a shaft c⁵ having a feed roller c⁶ mounted thereon and rotated thereby, while above the roller c⁶, in each side of the frame a, are slide blocks c⁷ which carry a roller c⁸ which is forced into contact with the roller c⁶ by means of springs c⁹, and forming the paper feeding mechanism. The gear c³ also engages a gear d, on the opposite side thereof, and which is mounted upon a shaft d² which carries the platen roller d³, provided with a blanket d⁴ of suitable material detachably mounted thereon, and the gear d is also enmeshed with a gear d⁵, directly thereover, with which is connected the printing roller d⁶ and upon which is mounted an electrotype d⁷ in the usual or any desired manner.

The printing roller d⁶ is recessed to receive readily removable type e, intended for subject matter requiring frequent changing, said type being held by means of a block e² pivoted at e³ to the roller, said block being normally forced against the type e by means of springs e⁴, clearly shown in Figs. 8 and 9, and, in order to release the pressure of the block from the type, we provide a hole e⁵ in the said block adapted to engage a pin or other suitable equivalent, as shown in Fig. 9, whereby the said block may be moved upon its pivot, against the springs.

To the rear of the platen roller d³ is a rigidly but detachably mounted blade f, beneath the paper strip, while above the said paper, and operating in conjunction with the blade f, is a knife or blade f² movable vertically in suitable guides by means of a finger b⁵ on the shaft b and, when said finger moves

the knife f^2 downwardly, the paper strip is cut into certain lengths, after which the knife is again drawn upwardly by means of springs f^3 connected with an overhead support f^4 .

Upon a stud h , beneath the mutilated gear b^4 , is a Geneva gear h^2 , indicated in dotted lines in Fig. 2 and shown in full lines in Fig. 12, operated by the mutilated gear b^4 and secured to the said gear h^2 is a disk h^3 to which is pivotally connected a link h^4 in turn pivoted to a lever h^5 secured to a shaft h^6 , rotatable in the frame a and extending therethrough, and which carries a similar lever h^7 on the other end thereof, said levers having each an arm h^8 pivotally connected therewith and which carry the ink roller h^9 .

Connected with each side of the frame a , above the printing roller, is a track i provided with a depression i^2 to receive wheels i^3 connected with the ink roller and which move on said tracks and, as shown at i^4 , we provide springs to control or insure the contact of said wheels with said tracks.

25 Rotatably mounted at k , upon the support f^4 , is an ink plate k^2 which carries an annular ratchet k^3 upon its under side, and also pivoted at k is a lever k^4 , which carries a pawl k^5 provided with a counterbalance k^6 , and which is adapted to be moved forwardly by a post k^7 upon the lever k^7 , and rearwardly by means of a contractile spring k^8 , and, as will be seen in Figs. 1, 4, 5 and 6, the pawl k^5 is in operative connection with the ratchet k^3 and 35 when the levers h^5 and h^7 are moved forwardly by the rotation of the Geneva gear h^2 the lever k^4 is also moved forwardly and the pawl thereon rotates the ink plate k^2 over which the ink roller moves, and when the ink 40 roller is in the position of the depressions i^2 it is permitted to touch the type faces on the printing roller, as shown in Fig. 6, after which the ink roller again passes over the ink plate for re-inking, into the position shown 45 in Fig. 5.

In the operation of our invention, the end of the paper strip is passed between the guides a^5 and a^6 , thence between the rollers c^6 and c^8 and thence between the printing 50 and platen rollers and the press is ready for use. In the position of the parts shown in Figs. 1, 2 and 4, the mutilated or toothless portion of the gear b^3 is about to engage the Geneva tooth of the gear c^2 , upon rotation of 55 the wheel b^2 in the direction of the arrow, and when these parts are so engaged, the feeding rollers, as well as the printing roller and platen are held inactive, but the shaft b still rotating, the finger b^5 thereon moves the 60 knife f^2 downwardly and the paper strip is cut, forming a slip or ticket of a desired size, and, when the finger b^5 passes the said knife, the latter is free to rise by means of its springs f^3 . At the beginning of this movement, the 65 mutilated part of the gear b^4 has passed the

Geneva tooth of the gear h^2 and the latter is being rotated, thereby moving the ink roller over the ink plate, upwardly, and afterward downwardly into the position of inking the type faces shown in Fig. 6, at which time the 70 mutilation of b^4 and Geneva tooth of h^2 are in conjunction and the gear h^2 is inactive, thereby holding the ink roller in this position. At approximately the moment the ink roller reaches this position, the teeth of the gears 75 b^3 and c^2 are again enmeshed and the rollers c^6 and c^8 again feed the paper and the printing roller and platen are again rotated, thereby moving the detached slip of paper and printing the same until the Geneva gear c^2 80 is again rendered inactive, when the operation described is repeated.

By means of this invention it is possible to print and detach tickets or the like from the paper roll at great speed and with a high 85 character of printing and it is evident that our press is applicable to a great variety of uses and can be built of a size depending upon the class of work to be performed thereon, being particularly adapted, however, as hereinbefore stated, to use in offices and the like for the printing of filing slips, tickets, etc. which are required daily or even hourly, with changed subject matter, and which could not wait for the usual method of 95 sending to a printing establishment. It will also be apparent that the electrotype can be quickly replaced by another, if desired, and means for adjusting the size of the detached slip can easily be added to our machine, it 100 being preferable, however, that a machine be constructed for each specific use and various other changes in and modifications of the form of construction shown and described may be made, and reserving the right to all 105 such modifications, within the scope of the following claims,

What we claim as new, and desire to secure by Letters Patent, is:—

1. A printing press, comprising a frame 110 having a roll of paper thereon, a power shaft, a printing roller having type thereon actuated by said shaft, an inking roller, a gear for actuating the same and a mutilated gear on said shaft and intermittently actuating said 115 gear and thereby said ink roller.

2. A printing press, comprising a frame having a roll of paper thereon, a power shaft, a mutilated gear at one end thereof, printing mechanism actuated intermittently thereby, 120 a mutilated gear on the other end of said shaft, inking devices actuated intermittently thereby, said movements occurring alternately.

3. A printing press, comprising a frame 125 having a roll of paper thereon, a power shaft, a printing roller having type detachably mounted thereon and actuated by said shaft, an inking roller, a gear for actuating the same and a mutilated gear on said shaft for 130

intermittently actuating said gear and thereby said ink roller.

4. A printing press, comprising a frame having a roll of paper thereon, a power shaft, 5 a printing roller having type thereon and actuated by said shaft, an ink roller, a gear for actuating the same, a mutilated gear on said shaft for intermittently actuating said gear, an ink plate and means for rotating the same 10 in the movement of said ink roller.

5. A printing press, comprising a frame having a roll of paper thereon, a power shaft, a mutilated gear on one end thereof, printing mechanism actuated intermittently thereby, 15 a mutilated gear on the other end of said shaft, inking devices actuated intermittently thereby and paper cutting means in operative connection with said shaft.

6. A printing press, comprising a frame 20 having a roll of paper thereon, a power shaft, a mutilated gear at one end of said shaft, a printing roller, a platen roller, feeding rollers, said rollers being actuated intermittently by said mutilated gear, a mutilated

gear on the other end of said shaft, pivoted 25 arms, an ink roller carried thereby, and a gear in operative connection with said arms and actuated intermittently by said last named mutilated gear.

7. A printing press, comprising a frame 30 having a roll of paper thereon, a power shaft, a mutilated gear on one end thereof, a stud, a gear thereon in operative connection with said mutilated gear, a feeding roller, a printing roller, a platen roller, a gear on each of 35 said rollers and a supplemental gear on said stud for actuating said rollers when said first named gear is actuated.

In testimony that we claim the foregoing as our invention we have signed our names 40 in presence of the subscribing witnesses this 13th day of October, 1908.

FREDERICK W. GEISSENHAINER.
